[57] CLAIM

The ornamental design for an electronic pedometer, as
shown and described.

DESCRIPTION

FIG. 1 is a front perspective view of an electronic pedometer showing our new design with the cover pivoted into its open position;

FIG. 2 is a rear perspective view thereof with the cover in its closed position;

FIG. 3 is a front perspective view thereof with the cover in its closed position;

FIG. 4 is a top view thereof with the cover in its closed position;

FIG. 5 is a side elevational view thereof with the cover in its closed position, the opposite side being a mirror image thereof; and,

FIG. 6 is a bottom plan view thereof with the cover in its closed position.

FIG. 3

FIG. 2

FIG. 1

FIG. 4

FIG. 5

FIG. 6
